SPARK PLUG

Filed Feb. 11, 1927

UNITED STATES PATENT OFFICE

EARL J. JOHNSON, OF SILVERBOW, MONTANA

SPARK PLUG

Application filed February 11, 1927. Serial No. 167,556.

The present invention relates to improvements in spark plugs, and the primary object of the invention is to provide an improved spark plug embodying features whereby the central electrode of the plug is readily removable from the body portion of the plug for the purpose of cleaning the electrode.

A further object of the invention is to provide a spark plug having a removable central electrode which may be readily removed for the purpose of cleaning or heating of the electrode without removal of the body portion of the plug from its threaded connection with the engine.

A further object of the invention resides in the provision of a spark plug embodying a removable electrode which when removed from the body portion of the plug provides an opening or way through the plug whereby the engine may be primed by introducing gasoline or analogous fuels through the way for the electrode.

A further object of the invention resides in the provision of a spark plug having a removable central electrode so detachably connected at its outer end to the outer end of the plug, as to insure the forming of an air tight and leak proof joint between the removable electrode and the body portion of the plug when the electrode is in position within the plug body portion.

A still further and important object of the invention resides in the provision of a spark plug as set forth, embodying relatively few and simple parts, and one wherein the parts are readily replaceable.

Other objects and advantages of the invention will be apparent during the course of the following detailed description, taken in connection with the accompanying drawing forming a part of this specification and in which drawing:

Figure 1 is a view illustrating the various parts of the plug in disassembled relation.

Figure 2 is a central longitudinal section through the plug and showing the parts in assembled operative relation.

Figure 3 is a view part in side elevation and part in longitudinal section, and show-

ing the manner in which the central electrode is moved into leak proof engagement with the shoulder provided in the insulating core.

Figure 4 is a transverse section on line 4—4 of Figure 3 and looking in the direction of the arrows.

Figure 5 is a transverse section on line 5—5 of Figure 2.

Figure 6 is a view illustrating the manner in which the central electrode may be cleaned by holding the firing point thereof over a flame for removal of the oil and carbon deposits from the firing point of the electrode.

In the drawing, and wherein similar reference characters designate corresponding parts throughout the several views, 10 designates a metal shell of the usual construction, embodying the wrench engaging portion 11, and the reduced threaded portion 12 which is intended for threaded engagement within a threaded opening of the engine block. The shell 10 is provided at its inner end with the usual electrode 13 which is grounded through the shell to the engine. The shell is provided with the usual internal seat 14 against which the packing washer 15 seats, and threaded into the upper end of the wrench portion 11, is the usual packing gland or nut 16.

This shell 10 and packing nut 16 are of usual and well known construction, and in the present invention, serve to support the porcelain or insulating core 18, and which insulating core is provided with an enlarged portion 19 which is intended to be moved by means of the packing nut 16 into sealing engagement with the washer 15. This insulating core 18 is provided with an axially disposed way or port 20 which extends from the inner to the outer ends of the core, and the way is reduced in diameter at its inner end as at 21, for providing an annular shoulder or seat 22 adjacent the inner end of the core. The extreme outer end of the way 20 is enlarged as at 23, and opening into the enlarged portion 23, at diametrically opposite points, are key ways 24 which open at the outer end of the core 18 and preferably converge toward their inner ends as illustrated in Figure 2. Provided adjacent the outer end

of the core 18, is an annularly extending groove 25, and the object of this groove will be subsequently set forth. As in usual construction, upon removal of the packing nut 16, the insulating core 18 may be readily withdrawn from the metal shell 10.

Mounted for detachable connection with the core 18, is a central electrode 30 embodying a stem portion 31 of cylindrical formation for slidably and rotatably fitting within the bore 20. The inner end of the stem 31 is reduced in diameter as at 32 for forming a firing point, and which reduced portion provides an annular shoulder 33 which when the stem is properly inserted in the way 20, is intended to engage the annular seat 22 provided adjacent the inner end of the way. Carried by the outer end of the stem portion 31, and which stem portion may be formed 20 of Monel or any other suitable metal, is a metallic head 35 which may be connected with the stem in any suitable manner, and in the example shown the head 35 is provided with a bore 36 having a threaded inner end for 25 threaded connection with the reduced screw threaded terminal portion 37 of the stem. The head 35 is preferably provided at its inner end with knurled portions 38 providing an annular groove 39, and the outer end 30 of the head is preferably of spherical formation and provided with a transverse slot 40. The annular groove 39 and spherical outer end of the head 35 provide means for receiving different types of conductor terminals which are to be electrically connected with the stem 31 for creating a spark between the electrode 13 and the firing point 32 for igniting of the explosive charge in the cylinder of the engine.

40 Fitting within the outer end of the core 18, is a plug 41 embodying a tubular sleeve portion 42 provided with diametrically disposed keys 43 which are intended to engage in the keyways 24 with the outer ends of the keys disposed flush with the outer end of the core 18. This tubular sleeve portion 42 slidably fits within the enlarged way portion 23 with the inner end of the sleeve abutting against the shoulder 44 formed by providing the enlarged way portion 23. The outer end of the sleeve portion 42, and which projects past the outer end of the keys 43, is externally threaded as at 45 for threaded reception of the head 35. As will be observed, the bore 36, adjacent its open end, is enlarged and threaded as at 46 for threaded reception of the threaded sleeve portion 45. As will be observed in Figure 2, the internal diameter of the sleeve portion 42 is of a diameter to slidably receive in snug fitting engagement, the stem portion 31 of the electrode 30. This plug 41, and which may be formed of any suitable metal, serves as means for 50 detachably connecting the central electrode

30 at its outer end, to the outer end of the core 18.

Carried by the outer end of the core 18, is a retaining cap 48 embodying a ring portion 49 engaging the side of the core, and a flat disc or plate portion 50 which is adapted to engage the flat end face 51 of the core and rest upon the outer ends of the keys 43 for retaining the plug 41 within the outer end of the bore or way 20. The inner edge of the ring portion 49 is crimped or curled into the annular groove 25 as in Figure 2, and this crimping or curling of the inner end of the ring serves to retain the cap 48 in position upon the outer end of the core 18. As will be observed in Figure 2, the threaded extension 45 of the sleeve portion 42 projects through the plate 50, and this plate is preferably adapted for threaded connection with the extension 45.

Disposed about the threaded sleeve extension 45, between the cap plate 50 and the head 35, is a yieldable gasket or washer 55, and this washer may consist of a copper shell provided with a packing such as asbestos or any other suitable material which may be readily compressed upon tightening of the central electrode 30. This compressible washer 55 has been provided in order that the shoulder 33 of the electrode 30 may be moved into sealing engagement with the core 22 when the electrode 30 is properly positioned within the core 18. The slot 40 provided in the head 35 will permit of the head being rotated by a screw driver when positioning and removing the electrode 30.

When desiring to remove the central electrode 30 in order that the firing point 32 of the electrode may be cleaned so that a proper spark will be produced between the point 32 and the electrode 13, it is merely necessary to rotate the head 35 until the head becomes disconnected from the threaded sleeve extension 45, and after which the stem of the electrode may be readily withdrawn from the way 20 without requiring the removal of the shell 10 from its connection with the engine. During removal and replacing of the central electrode 30, the keys 43 of the plug 41, will prevent the plug from rotating in either direction, and the cap 48 will serve for retaining the plug 41 in proper position at the outer end of the core 18. After removal of the central electrode, the firing point 32 may be scraped for removing the carbon deposit therefrom, or may be held over a flame in a manner as illustrated in Figure 6 for burning of the carbon deposit from the firing point of the electrode. This heating of the stem portion of the central electrode not only serves to remove the carbon deposit from the firing portion 32, but also heats the electrode in a manner whereby when the electrode is again positioned within the core 18, the heat radiated from the stem 130

will serve to vaporize a portion of the explosive charge at the inner end of the spark plug and result in ready and easy starting of the engine, particularly in cold weather. It will further be seen that upon removal of the central electrode 30, that an opening is formed through the core 18 whereby gasoline or the like may be introduced through the way 20 for priming of the engine.

From the foregoing description it will be apparent that a novel and practical type of spark plug has been provided which is of extremely simple construction, and which plug embodies a central electrode which is readily detachably connected at its outer end to the outer end of the plug, and which central electrode by means of its detachable connection with the body portion of the plug, will permit of the ready cleaning of the electrode without removal of the plug from the engine block, will permit of the electrode being heated for aiding in starting of the engine, and which electrode when removed allows for an opening to be formed through the plug whereby fuel may be introduced into the engine through the plug for priming of the engine.

Changes in detail may be made to the specific form of the invention herein shown and described, without departing from the spirit of the invention or the scope of the following claims.

I claim:

1. A spark plug, an insulating core having an axial way therethru and elongated keyways extending longitudinally of and opening into the way at the outer end of the core, a stem removably extending thru the way, and retaining means for the stem comprising a plug embodying elongated keys slidably fitting in said keyways with the outer ends of the keys flush with the outer end of the core and an externally threaded extension projecting past the outer ends of the keys, a retaining cap embodying a plate portion in overlying engagement with the outer ends of the keys and a ring portion for crimped engagement circumferentially of the core, and a terminal head carried by the outer end of said stem for threaded connection with the threaded extension of said plug.

2. A spark plug, an insulating core having an axial way therethru provided intermediate its ends with an outwardly facing annular seat, a stem providing a central electrode, slidably and rotatably fitting in said way and having a reduced inner end portion providing an annular shoulder engageable with said seat, and retaining means for sealing the stem in said way comprising a plug fixedly mounted in the outer end of said core and having an externally threaded tubular extension aligning with said way, a terminal head carried by the outer end of the stem and having a bore for threaded connec-

tion with said extension, and a compressible sealing ring encircling the tubular extension between the terminal head and outer end face of said bore for allowing seating of said stem shoulder upon said seat and forming a seal in said way of the insulating core.
